CLAIM

We claim the ornamental design for a wrist-worn electronic device, as shown and described.

DESCRIPTION

FIG. 1 is a front perspective view of a wrist-worn electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is a rear-bottom perspective view thereof.

(Continued)

The broken lines in the drawings illustrate portions of the wrist-worn electronic device that form no part of the claimed design.
